UNITED STATES PATENT OFFICE.

EZRA B. SMITH, OF CHICAGO, ILLINOIS.

PNEUMATIC CUE.

1,279,925.

Specification of Letters Patent. Patented Sept. 24, 1918.

Application filed April 10, 1915. Serial No. 20,517.

To all whom it may concern:

Be it known that I, EZRA B. SMITH, a citizen of the United States, residing at Chicago, county of Cook, State of Illinois,

5 have invented a certain new and useful Improvement in Pneumatic Cues, and declare the following to be a full, clear, and exact description of the same, such as will enable others skilled in the art to which it pertains 10 to make and use the same, reference being had to the accompanying drawings, which form a part of this specification.

My invention has for its object to produce a simple and efficient pneumatic cue for use 15 in miniature pool and billiard games, by means of which miniature balls may be driven in the same manner and with the same precision as in the ordinary full size games of this kind.

20 The various features of novelty whereby my invention is characterized will herein-after be pointed out with particularity in the claims; but, for a full understanding of my invention and of its object and advan- 25 tages, reference may be had to the following detailed description taken in connection with the accompanying drawing, wherein:

Figure 1 is an elevation of a cue arranged in accordance with my invention;

30 Fig. 2 is a longitudinal axial section on an enlarged scale, through what may be termed the head of the cue;

Fig. 3 is a view similar to Fig. 2, illustrating the rear end of the head with the driv- 35 ing member in its retracted position; and

Fig. 4 is a section on line 4—4 of Fig. 3.

Referring to the drawing, 1 represents a long slender tube having the front end, 2, reduced in diameter and tapered gradually 40 so as to give the effect of a pointed end. Within the tube is a spool-shaped piston, 3, fixed to the inner end of a rod, 4, which projects out through and is guided by the pointed end of the tube. On the outer end of the 45 rod is secured a small cup-shaped member, 5, containing in the outer end a cushion, 6, preferably of rubber; this cushion projecting far enough so that it alone engages the ball when the cue is operated. At the rear 50 end of the tube is a nipple, 7, upon which is slipped one end of a flexible tube, 8, having at its other end a compressible bulb, 9.

Upon pressing the bulb, the air behind the piston forces it forward at a speed depend- 55 ing upon the manner in which the bulb is pressed. Thus if the bulb is pressed quickly

and sharply, the piston and rod will be shot forward at a high speed so as to be capable of delivering a strong blow while, on the other hand, if the bulb is pressed less quickly, the movement of the piston and rod will be less rapid and a softer blow may be struck.

The piston has simply a nice sliding fit within the tube, because packing of any kind would impede its movement. Consequently if the bulb is kept compressed for a short time, the air will leak past the piston, although this leakage will not be sufficient to interfere with the positive operation of the piston in striking a blow. In the reduced end of the tube are openings, 10, which permit the air to escape in advance of the piston and which also permit the air to enter freely in front of the piston and 70 drive it back when the bulb is released. In order to prevent the piston from making a tight seal when it is shot forward and held there momentarily, I form on the front end thereof a projection, 11, somewhat smaller 75 in diameter than the piston, this projection preventing the piston from seating itself tightly in the rear end of the reduced portion of the tube. This arrangement permits the air to leak past the piston in both direc- 80 tions when at the front end of the tube, insuring that sufficient air will pass out of the tube from behind the piston at each stroke to bring about a quick return of the piston, and also permitting sufficient air to leak in- 85 wardly if the bulb should be held compressed too long, to allow the bulb to be filled with air at atmospheric pressure.

As heretofore stated, if the piston is packed the packing interferes with its free 90 movements back and forth, but the very fact that the piston is left entirely free gives rise to the disadvantage that the piston and rod will drop down if the head of the cue is held upright or at any considerable angle 100 to the horizontal, as it will naturally be held in making many of the shots in a billiard or pool game.

In order to hold the piston in its retracted position and at the same time permit it to 105 move freely in making a stroke, I have provided a small spring finger which engages with the piston, when retracted, and yieldingly holds it with just sufficient pressure to prevent the weight of the piston and its 110 rod from causing them to drop. The impact required to release the piston is very

slight so that as soon as the bulb is compressed the piston travels forward without any appreciable hesitation in starting, that is without permitting any considerable rise 5 in pressure behind the piston to take place before the piston begins to travel.

In the particular arrangement shown, I have made the rear end of the piston cup-shaped so as to provide a rearwardly-opening 10 chamber, 12. The resilient member consists of a loop, 13, of light spring wire, the major portion of which lies just in front of the nipple, 7 while its arms project rearwardly into the nipple; one of the arms being extended into and preferably through 15 a slot, 14, cut in the rear end of the nipple. The free end of this latter arm may be laid along the outer side of the nipple as indicated at 15 so that when the flexible tube is 20 slipped over the nipple it assists in holding the spring member in place. Of course the slot 14 may be closed upon the arm of the spring member so as to hold it securely in place. The free arm of the spring member 25 is made only long enough to permit it to extend into the nipple and act as a guide. The parts are so proportioned that when the piston comes back as indicated in Fig. 3, the spring loop enters the chamber 12 and 30 holds the piston with a very light pressure. When the bulb is compressed, however, the first slight increase in pressure in the air behind the piston drives it forward and releases it from the holding device so that it 35 may travel forward freely.

While I have illustrated and described with particularity only a single preferred form of my invention, I do not desire to be limited to the exact structural details, thus 40 illustrated and described; but intend to cover all forms and arrangements which come within the terms employed in the definitions of my invention constituting the appended claims.

45 I claim:

1. A pneumatic cue including an elongated tube, a piston slidable within the tube, a stem projecting from said piston at one end of the tube, an air compressing device 50 connected to the other end of the tube, and means at the latter end of said tube for yieldingly holding the piston against movement toward the other end.

2. A pneumatic cue including an elongated tube, a piston slidable within the tube, a stem projecting from said piston at one end of the tube, an air compressing device connected to the other end of the tube, and means yieldingly engaging the piston at a 60 predetermined point in its backward stroke and adapted to hold it against forward movement.

3. A pneumatic cue including an elongated tube, a piston slidable within the tube, a stem projecting from said piston at one end 65

of the tube, an air compressing device connected to the other end of the tube, and a spring finger frictionally engaging with said piston when it reaches a predetermined point to hold it yieldingly against movement in a direction to strike a blow. 70

4. A pneumatic cue including an elongated tube, a piston slidable within the tube, a stem projecting from said piston at one end of the tube, an air compressing device 75 connected to the other end of the tube, said piston having an elongated chamber opening out of the rear end thereof, and a spring finger arranged in the tube in position to enter said chamber and yieldingly hold the 80 piston against movement when the piston is retracted.

5. A pneumatic cue including an elongated tube, a piston slidable within the tube, a stem projecting from said piston at one 85 end of the tube, an air compressing device connected to the other end of the tube, said piston having an elongated chamber opening out of the rear end thereof, a spring wire arranged in the form of a loop having 90 one end fixed to the tube at the rear end thereof, the loop being in position to enter the chamber in the piston when the piston is retracted, and yieldingly hold it against forward movement. 95

6. In a pneumatic cue, a tube, a piston arranged within the tube, a piston rod extending from the piston out of the front end of the tube, the front end of the tube being gradually reduced in diameter to give it a 100 pointed appearance, there being openings through the pointed end of the tube to permit the entrance and exit of air in advance of the piston, and said piston having a forward projection somewhat smaller in diameter than that of the largest portion of the piston, to prevent the piston from making a tight joint at the front of the tube when the piston is shot forward. 105

7. A device of the character described 110 comprising a pneumatic projector having a rigid elongated aiming part shaped approximately like a slender pointed pencil, a striking device movable lengthwise of said part in and out through its pointed end, means for yieldingly holding the striking device retracted, a flexible tube connected to the opposite end of said aiming part, and an air compressing device connected to said tube. 115

8. A pneumatic cue comprising an elongated slender tube, a striking device movable lengthwise within the tube and projecting out through one end thereof, an air compressing device connected to the other end of the tube, and means for yieldingly holding said striking device in its retracted position whenever it reaches that position. 120

9. A pneumatic cue including an elongated tube, a piston slidable within the tube, a stem projecting from said piston at one 130

end of the tube, an air compressing device connected to the other end of the tube, and means for yieldingly holding the piston and the stem in a retracted position whenever 5 they reach such position.

10. A pneumatic cue comprising an elongated tube, a striking device arranged within the tube and movable lengthwise thereof, one end of the striking device projecting be-

yond the tube, an air compressing device 10 connected to the tube at the opposite end of the striking device, and means for yieldingly holding said striking device in its retracted position whenever it reaches that position. 15

In testimony whereof, I sign this specification.

EZRA B. SMITH.
